UNITED STATES PATENT OFFICE.

JONA. HILLER AND JOS. BULLOCK, OF COHOES, NEW YORK, ASSIGNORS TO WILLIAM SMITH, OF ALBANY, NEW YORK.

KNITTING-MACHINE.

Specification of Letters Patent No. 22,769, dated January 25, 1859.

To all whom it may concern:

Be it known that we, JONATHAN HILLER and JOSEPH BULLOCK, of Cohoes, Albany county, State of New York, have jointly invented certain improvements in that part of the apparatus of knitting-machines known as the "stop-motion," whereby on the failure of the stitch or any other irregularity in the operation of the machine the integrity 10 of the fabric is broken or deranged the machine is stopped from working until the defect can be repaired; and we declare the following specification, with the drawings hereto attached as part of the same, to be a 15 full and perfect description thereof.

Figure 1 represents in perspective a knitting machine with our invention applied to it; Figs. 2 and 3 diagrams of the stop carriage with its working apparatus.

Similar letters in the different figures denote the same parts of the apparatus.

Our invention is attached to what is known as Bailey's circular knitting machines, one of which is represented in the 25 drawing. It is a strong stand A, A, upon which is elevated upon short pillars the knitting apparatus B, B.

In the drawing the revolving circle B and the needles K are represented, but the burs 30 and other machinery for forming the stitches are omitted as not necessary to illustrate the stop-motion.

From the points of the needles depends the fabric F as fast as it is knit; the integrity 35 of the cloth depending upon each needle making a perfect stitch; so that whenever a needle fails to do so, and a stitch is dropped, a gap occurs in the work which unless repaired at once is repeated at the 40 same point leaving a serious defect in the article. To obviate this difficulty and stop the machine promptly, on the least irregularity in this respect is the object of what is called a stop motion several of which have 45 been made, all more or less defective in certainty and promptness of action, defects which we claim to have remedied by our invention.

A rectangular flat plate C is attached to 50 the revolving circle B. The outer and inner edges of this plate, which we will call the stop carriage, are turned up into, or terminated by upright ledges D, D, through which by slots therein, two parallel flat sides 55 G and H pass, and are free to move back-

ward and forward in their slots. The inner end of H projects far enough to reach beyond the needles and be turned down and outward, so as to form a hook or finger, the lower part being terminated by a point sharp enough to pass into any breach left by a dropped stitch without cutting the fabric against which it must pass steadily as it proceeds around the circle of needles just below their hooks or points. The necessary pressure is kept up by a light (spiral) spring a attached to the outer edge of the carriage at one end, and at the other to an upright pin b upon the slide. The slide G is kept habitually pressed outward by a similar device and arrangement of spring from the end of the carriage to pin c upon the slide. The outer end of this slide is sloped or beveled in a horizontal direction. This same outer end overlies the movable 75 ring R which forms the outer edge of the machine but moves freely without attachment to the circle B.

Upon this ring at short intervals are fixed upright pins p, p, so arranged that when the outer end of slide G is drawn outward by its spring it will lie between the pins, but when held inward will clear the pins. At any point of the ring a horizontal pin J is inserted into its periphery. The object of this pin is to move the ring and disengage the driving machinery from the knitting apparatus, as follows:

The belt pulley P runs loose upon the shaft S, at one end of which is the bevel-wheel L which meshes into teeth on the underside of the rotary circle B. At the other end of the shaft is fixed a coupling-box M a corresponding box N being attached to the pulley P. P is connected in 95 the usual way by a forked arm O with the hand lever T by whose movement it can be coupled or uncoupled into M, the spring X holding the lever so as to keep them uncoupled.

A horizontal detent lever U is pivoted upon the stand W with its inner limb projecting to near the ring R, and from it rises a pin e, the detent being kept pressed against T by the spring d so that when T is drawn back it will catch and hold it in the notch of the detent, thus coupling the machinery and putting in motion the circle B and the entire knitting apparatus.

At the beginning of operations the pin J 110

is placed behind and against the pin *c*, at *f*, by moving the ring *R*, so that any movement of the ring from left to right may shift the detent and uncouple the moving power. The ring is intended to move only upon the occurrence of a breach in the fabric, and by its connection with the operations of the stop carriage which is thus: The slide *H* (as shown) is kept drawn inward whenever the cloth is whole. The slide *G* is drawn inward and kept in that position by a dog or pawl *g* with its spring (see Figs. 2 and 3) pivoted upon the plate *G*, the pawl having two arms, the one holding into a notch *h*, and the other extending over slide *H*, upon which slide a movable gage *i* is affixed by which the distance slide *H* shall move, before tripping *g* and disengaging slide *G*, can be adjusted so as to act upon a small or greater break of the fabric. So long as the slide *G* shall be held by the pawl its outer end will pass behind the pins *p*, but the moment that the outward pressure of *H*, by the gage touching the pawl trips *g* and releases *G*, its outer end springs out between the pins, and by contact with one moves the ring *R* and disengages the driving power. In order to set the slides after each stoppage, conveniently there is an adjunct apparatus, consisting of a lever *Y* pivoted upon the inward projection of slide *H*. It is three-pronged *l* forming a handle *l* and *m* stops. In Fig. 2 the apparatus is in a position to leave the slides free to move. By turning the handle *l* to the left *l* will rest against the inner ledge of *G*, (as shown in Fig. 3,) while *m* holds slide *G* so that the pawl *g* shall enter its notch *h*. This being done and the circle *R* moved so that the pin *J*, (which after each stoppage will lie as shown in Fig. 1) shall be at *f*: the lever *Y* is shifted to lie as in Fig. 2 and the machine put in motion. Should lever *Y* be left as in Fig. 3 the slide *H* would remain immovable and its point pass over the defective spots. To prevent such a result from the carelessness of attendants pins *r*, *r*. are at-

tached to any convenient parts of the frame so as to intercept the handle *l* before the carriage shall have traveled far in its circuit, and so the contingency of a large breach occurring before the mischief is detected be avoided.

The advantages of this machine are these: The stop motions now in use depend upon the action of a slide the finger being at one end of it, and the other end intended to catch the pins on the circle. Now whenever a very small defect or depression occurs, the finger will not pass deeply enough under the needles to allow the slide to pass beyond a pin, whereas in our machine the slightest depression will move the finger slide *H* so as to disengage *G*, which then is thrown out to its full extent. Should the break occur when the slide is opposite a pin it will strike against it, and slide along it, but by the time its edge passes the pin the finger will have reached firm cloth and hold the slide back, whereas whatever may be the movement of slide *H* after *g* is tripped the moment *G* passes a pin it will press out and strike the next pin of the ring and stop the machine.

We do not claim a slide operating by a bent arm at one end, to enter breaches in the fabric, and at the other by moving a ring which is attached to and operates it, shift a coupling apparatus.

We claim—

The apparatus attached to the stop carriage: viz: the combination of the slides *H* and *G*, pawl *g*, gage *i*, and arm *m* operating together upon the breaking of the fabric to uncouple the driving power, by and in combination with the ring *R*, pin *J*, and spring *d*, which release the detent *U*, substantially in the manner and for the purposes set forth in the within specification.

JONATHAN HILLER.
JOSEPH BULLOCK.
